BUFFING WHEEL

Henry H. Bahr, New York, N. Y., assignor to
 Guaranteed Buff Co., Inc., New York, N. Y.,
 a corporation of New York

Application May 29, 1947, Serial No. 751,271

7 Claims. (Cl. 51—193)

1

The present invention is directed to buffing wheels, more particularly of the type wherein fabric or similar material is mounted on a suitable hub and rotated at high speed.

Various structures of this type have previously been used but certain disadvantages are inherent in such prior art structures. For instance, in one such construction, pieces of fabric were sewed together and cords provided along the edges thereof which were in turn secured to a rotatable drum. In such structure, the speed of rotation was such that the cords did not hold securely in the hub and the pieces of fabric were so spaced that an inadequate buffing effect was obtained.

In another structure of this character there was provided a wheel of metal having a recess on the periphery thereof and pieces of leather or the like were introduced into the periphery and extended outwardly therefrom. This had numerous disadvantages in that the assembly of the pieces was a slow and tedious task, as each piece had to be inserted individually into a slot and considerable time and effort was wasted in the procedure. Furthermore, the pieces of leather were loosely mounted so that they had a tendency to move relatively to each other during the buffing operation and often such pieces tore and pulled out of the wheel.

The present invention is intended and adapted to overcome the difficulties and disadvantages inherent in prior structures of this type, it being among the objects of the present invention to provide a structure of buffing wheel which is sturdy in construction and capable of use over long periods of time with highly effective results.

It is also among the objects of the present invention to provide a buffing wheel which is simple and easy to assemble and wherein the pieces of fabric are held in predetermined relationship without any danger of such pieces becoming loosened or tearing out.

It is still further among the objects of the present invention to provide a buffing wheel of the type described wherein air may be provided for cooling purposes, buffing compounds in liquid form or various other degrees of viscosity may be contained therein, and wherein a plurality of units may be assembled to provide a single unit.

These and other objects of the invention will be apparent from the following description and the accompanying drawing constituting a part hereof, and in which like reference characters indicate like parts.

Fig. 1 is a vertical cross-sectional view taken through a buffing wheel made in accordance with

2

the present invention, some parts being shown in elevation;

Fig. 2 is a side elevational view of the buffing wheel shown in Fig. 1, some parts being omitted and other parts being broken away for clearness;

Fig. 3 is a fragmentary top view of said wheel;

Fig. 4 is a fragmentary side elevational view of a wheel made by a modified arrangement of the fabric pieces;

Fig. 5 is a vertical cross-sectional view taken through a wheel of modified form wherein an annular channel-like member is an essential element;

Fig. 6 is a fragmentary side elevational view of the form shown in Fig. 5.

Fig. 7 is a fragmentary vertical cross-sectional view of a modified form of buffing wheel wherein suitable staples, preferably belt hooks, are provided for holding the pieces of fabric;

Fig. 8 is a perspective view of a bundle of pieces of fabric constituting a part of the modification shown in Fig. 6;

Fig. 9 is a plan view, fragmentary in character, showing a modification similar to Fig. 6, but in which the pieces of cloth are in a plane parallel to the face of the wheel, and

Fig. 10 is a vertical cross-sectional view of an assembly of a plurality of wheels to provide a single buffing unit.

As shown in Figs. 1, 2 and 3, there is provided a plurality of pieces of fabric 1 which are cut on the bias, so as to provide a maximum of thread ends on the outer edge 4 of said pieces to enhance the buffing effect. Pieces 1 are cut so as to have a relatively narrow neck near base 3. The upper edge 4 and the side edges 2 provide the buffing surface.

Core 5 of wood, metal, synthetic resinous compositions or the like, has an opening 6 for mounting on a spindle. The periphery 7 thereof is spaced from base 3 to provide an annular space 8 between the same. A pair of disks 9 and 10 have their edges 11 curved inwardly and straddle core 5. Said edges may be provided with serrations 12 and have opening 13 registering with opening 6. Edges 11 are introduced into neck 14 of pieces 1 and clamped in place by a series of rivets 15. Preferably, and usually, pieces 1 are set at an angle other than a right angle to the face of disks 9 and 10. This angle may be of any desired extent in order to give the predetermined results.

Disk 10 is provided with an opening adjacent 55 to space 8 covered by a cap 16. A suitable liquid

buffing compound is introduced into space 8 and cap 16 retains the same. In operation, during the high speed rotation of the buffing wheel, the liquid by centrifugal action is caused to advance through base 3 of the pieces 1 and then outwardly to edges 2 and 4 where the liquid comes in contact with the article being buffed.

In the modification shown in Fig. 4, disks 9 and 10 are provided with a series of relatively large openings 18 communicating with space 8. A bundle of pieces of fabric 19 is stapled together as shown at 20 and a series of such bundles are clamped between disks 9 and 10 with spacers 21 between the same. By this construction, during the rotation of the buffing wheel, air is drawn into openings 18 and is ejected radially through spacers 21, thus maintaining the wheel and the work cool and preventing scorching of the fabric.

Referring to the modification shown in Figs. 5 and 6, there is provided an annular channel formed by two flanges in parallel relationship and a base 23 joining the bases of said flanges. The outer edges of flanges 22 are turned inwardly as shown at 24 and serrated or provided with prongs if desired. Pieces of fabric 1 are clamped between the same. This may be accomplished by first providing a channel-like member 22-23 without the inturned edges 24, assembling the pieces of fabric therein and then by a suitable tool bending over edges 24 into the necks of said fabric pieces.

Annular recesses 25 may be provided at the inner edges of said channel. A pair of spiders 26, having a central opening to accommodate spindle or shaft 17, have openings 27 therein. The legs of the spiders may be set at an angle to the plane of rotation, thus forming fan blades for the purpose of forcing air into the interior of the hub and from there through pieces 1 to the point of contact with the work. The outer edges of spiders 26 are formed annularly as shown at 28 so that they may fit over ring 23 and recess 25 formed in the channel member. Said spiders constitute a hub for mounting the buffing wheel on a suitable axle and said spiders may be secured to the channel member by any suitable means as by riveting, spot welding or by any other well-known device.

As shown in Figs. 7 and 8, there is provided a pair of disks 29 having central openings to accommodate spindle 17. Along the outer edges of said disks are a series of pins or rivets 30 passing between said disks and holding them in spaced relation. Pieces of fabric 31 are stapled together by belt hooks 32. Pins 30 pass through the free ends of hooks 32, thus holding bundles 31 flexibly but firmly in the buffing wheel. Pins 30 may be set so that the centerlines thereof are at right angles to the plane of disks 29. In such case the pieces of fabric constituting the bundle may be stapled together so that when mounted in the buffing wheel, the plane of the pieces of fabric is at right angles to the plane of said disks. In the alternative, pins 30 may be so positioned that they are not at right angles to the disks, in which case the pieces 31 are stapled together at an angle as shown in Fig. 8, so that the side edges of the bundles are in a plane parallel to the disks.

In Fig. 9 there is shown a modification of the invention wherein the pieces of fabric 33 are in a plane parallel to the plane of the disks. There is provided a bundle of pieces 33 and a series of such bundles are placed so that the centerlines 34 and adjoining edges thereof are radial. Rivets 35

pass through the bundles of pieces and are anchored in disks 36. Openings 37 are provided in said disks in order to provide a current of air for cooling the wheel and work while in operation.

It is often desirable to provide a relatively wide buffing surface and for this purpose a plurality of individual buffing wheels are assembled as a unit, as shown in Fig. 10. There is provided a shaft 38 having a shoulder 39 and a spindle 17 of lesser diameter is formed thereby, providing means for mounting a plurality of units. Washer 41 is placed against shoulder 39 and unit 43 mounted on spindle 17. Washer 42 is placed against unit 43 and unit 44 is mounted in contact with washer 42. Washer 42' is placed against unit 44 and unit 45 is mounted in contact with washer 42'. Nut 46 is threaded onto end 47 of spindle 17 and a washer 48 is interposed between nut 46 and spider 26. Thereby the entire assembly is held rigidly together as a unit having a relatively wide buffing surface.

Numerous advantages are inherent in the present construction:

It is possible to assemble a number of individual buffing wheels to provide a single wide wheel for the buffing of relatively large articles. Also by reason of the construction of the present wheel, there is readily obtained both front and side polishing action. The angle at which the pieces of fabric are mounted may be varied over a wide range, thereby accordingly changing the polishing and buffing qualities. The ventilating action described herein resulting from the blade-like side members of the wheel, prevents burning or scorching of the fabric and the melting of the polishing composition, by reason of the air being forced into the wheel, keeping the same cool.

The number of pieces of fabric may be varied so as to provide harder or softer buffing wheels without the necessity of using spacing disks of smaller diameters as in prior structures. The buffing action may be modified by providing alternate pieces of hard and soft material, such as a combination of muslin and flannel or sand paper and cloth, or the like. By reason of the angular location of the pieces, there is a shearing action provided, thereby giving better and more uniform buffing and polishing of the articles. By the term "fabric" as used herein it is intended to include not only textile fabrics but also any flexible sheet material adapted for use in wheels of the character described.

Although the invention has been described setting forth several specific embodiments thereof, such embodiments are intended to illustrate the invention and not to limit the same as many variations in the details of construction may be made within the spirit of the invention. For instance, the openings 18 and 37 may be of any desired size or shape and need not necessarily be circular. Space 8 in the modification shown in Fig. 1 may be omitted and core 5 may have its outer surface 7 substantially in contact with base 3 of the fabric pieces. The shape of neck 14 on said pieces 5 may be other than shown and it may even be a slot at right angles to the sides 2 of said pieces. The buffing edges 4 and/or 2 may be shaped to conform with the profile of the articles being polished so that said articles may be buffed completely in a single operation. The bases 3 of said pieces may be impregnated with suitable adhesive or resinous composition in order to give a solid mass and thus facilitating the mounting and additionally preventing the units from being torn 75 out of position. Said pieces need not be symmet-

rical and may extend laterally more on one side than on the other side of the wheel.

In the modification shown in Figs. 1 and 2, the depth of the fabric pieces may be substantially greater than shown and the hub or mounting for the same may be of relatively lesser diameter, thus increasing the life of the buffing wheel. There may be introduced rivets or pins 50 passing through the disks and the fabric pieces to more securely hold the same in place. Such rivets may also be provided on the other modifications described herein. The pieces of fabric as shown in Fig. 9 may be held in position otherwise than as shown, as for example by belt hooks, rings, staples, or the like.

Core 5 may be omitted and the sides 9 and 10 so constructed that they are in contact or they may be fixed in spaced position, if desired. Space 8 for holding buffing composition may be deeper or shallower than shown and described, depending upon the amount of such composition it is desired to carry in the space. Parts 22 and 23 may be made of several elements joined together or part 23 may be omitted entirely. The buffing wheels may be mounted on horizontal or vertical axes, and are suitable for side polishing and buffing.

There may be provided a disk-like base having a stub shaft secured on one face thereof. The other face has one or more concentric circular grooves. In each of the grooves there is placed a continuous strip cut on the bias and wound spirally to provide an annular member. If desired, a channel-like clip may be utilized to hold the convolutions together. After the strips are assembled in the grooves, radial pins may be introduced to further lock the same in position. Provision may be made in the base for openings to allow air to be drawn or forced through the buffing wheel adjacent to the fabric strips, in order to cool the same. Fan blades or the like may be provided to assist in the circulation of air. The fabric strips may be arranged in radial grooves, in which case the bundle or set of pieces is of corresponding shape, or such grooves may be curved and the strips arranged in such curved grooves similar to the blades of a centrifugal pump. Such a structure is adapted for use on its face and sides in buffing operations.

In a further modification, a disk is mounted on the end of a shaft and bundles of pieces similar to that shown in Fig. 8 held by belt hooks or staples are provided. A series of spaced radial or otherwise arranged holes is provided in said disk, the free ends of said hooks are passed through each of said series and wires or the like passed through said free ends at the back of the disk to lock the bundles in position. The face and side of the buffing wheel so formed may be used for polishing. To assist in the ventilating action in Fig. 5 openings may be provided in member 23.

These and other changes may be made in the details of the invention, which is to be broadly construed and limited only by the character of the claims appended hereto.

I claim:

1. A buffing wheel comprising a pair of disks spaced apart and in lateral alinement, means for mounting said disks on a shaft, a plurality of spaced pins connecting said disks adjacent to the periphery thereof, a plurality of sets of pieces of fabric secured together at one edge by staples, the ends of said staples fitting over said pins between said disks.

2. A buffing wheel comprising a pair of disks spaced apart and in lateral alinement, means for mounting said disks on a shaft, a plurality of spaced pins connecting said disks adjacent to the periphery thereof, a plurality of sets of pieces of fabric secured together at one edge by staples, the ends of said staples fitting over said pins between said disks, the axes of said pins being at an angle to said disks other than a right angle.

3. A buffing wheel comprising a pair of disks spaced apart and in lateral alinement, means for mounting said disks on a shaft, a plurality of spaced pins connecting said disks adjacent to the periphery thereof, a plurality of sets of pieces of fabric secured together at one edge by staples, the ends of said staples fitting over said pins between said disks, the width of said pieces being greater than the distance between said disks.

4. A buffing wheel comprising a pair of disks spaced apart and in lateral alinement, means for mounting said disks on a shaft, a plurality of spaced pins connecting said disks adjacent to the periphery thereof, a plurality of sets of pieces of fabric secured together at one edge by staples, the ends of said staples fitting over said pins between said disks, said fabric being bias cut to provide weft and woof thread ends on the outer edge thereof.

5. A buffing wheel comprising a pair of disks spaced apart and in lateral alinement, means for mounting said disks on a shaft, a plurality of spaced pins connecting said disks adjacent to the periphery thereof, a plurality of sets of pieces of fabric secured together at one edge of staples, the ends of said staples fitting over said pins between said disks, said pieces of fabric being at an angle to said disks other than a right angle.

6. A buffing wheel comprising a disk, means for mounting said disk on a shaft, a plurality of spaced pins secured to said disk adjacent to the periphery thereof, a plurality of sets of pieces of fabric secured together at one edge by staples, the ends of said staples fitting over said pins.

7. A buffing wheel comprising a disk, means for mounting said disk on a shaft, a plurality of spaced pins secured to said disk adjacent to the periphery thereof, a plurality of sets of pieces of fabric secured together at one edge by staples, the ends of said staples fitting over said pins, said fabric being bias cut to provide weft and woof thread ends on the outer edge thereof.
